UNITED STATES PATENT OFFICE.

HUBERT CLAUS, OF THALE-IN-THE-HARZ, GERMANY, ASSIGNOR TO
HERMANN AICH, OF NEW YORK, N. Y.

MACHINE FOR POWDERING SHEET METAL, &c.

SPECIFICATION forming part of Letters Patent No. 465,815, dated December 22, 1891.

Application filed August 13, 1891. Serial No. 402,554. (No model.)

To all whom it may concern:

Be it known that I, HUBERT CLAUS, a resident of Thale-in-the-Harz, Empire of Germany, have invented an Improved Machine for 5 Powdering Sheet Metal and other Substances, of which the following is a specification.

The main object of this invention is to produce a machine for evenly distributing powdered enamel or other dry powder upon steel, 10 iron, or other plates prior to melting said enamel and causing it to adhere as a coating to the said plates; but the invention is also applicable to the powdering of fabrics with flock or for analogous purposes.

15 The invention consists of the new combinations and arrangements of parts herein-after more fully described.

In the drawings, Figure 1 represents a vertical longitudinal section on the line 1 1, Fig. 20 2, of my improved powdering-machine. Fig. 2 is a plan or top view, partly in section, of said machine, the line 2 2, Fig. 1, indicating the plane of section.

The letter A in the drawings represents the 25 main frame of the machine. In the lower part of this frame are the bearings for two parallel shafts B and C, each carrying a pair of sprocket-wheels a and b, over which sprocket-wheels endless chains d d are placed. 30 These endless chains are indicated in Fig. 2 by double dotted lines and in Fig. 1 by single heavy dotted lines. The two endless chains d d are connected by slats e, made of wood or analogous substance and riveted or otherwise tied to the chains, and over these slats is placed an endless band, of wire-gauze f or 35 of analogous fabric. All these parts are arranged to constitute an endless carrier for the plates or articles to be powdered, said carrier being put in motion whenever rotary motion is imparted by a belt g (see Fig. 1) to 40 a pulley on the shaft C from a suitable driving-pulley h.

Suitable idle-wheels i are hung to the frame 45 A at proper intervals to support the chains d and the fabric apron f in a substantially horizontal position during their passage from one sprocket-wheel to the other. A suitable brush j is placed beneath the apron f to remove from its surface any powder which may 50 adhere thereto. Above this endless apron

the frame A extends and carries at its upper end a hopper D, the lower end of which is closed by converging flaps k, which can be moved close together or more or less apart by 55 suitable screws and nuts l or by other means. Below this hopper D is a shaft E, which is driven by a belt m or by other means from one of the driving-wheels, and which carries a series of brushes n n, said brushes being 60 arranged, by preference, in the convolute manner which is represented in Fig. 2 of the drawings. Below the shaft E is a semi-cylindrical sieve F, which is supported on the framing A in such manner that it may be 65 shaken by the agitator G, said agitator being a ratchet-like wheel actuating against a lug on a bracket o, that projects from the sieve F. The hopper-body D is connected with a downwardly - extending chamber H, which 70 reaches down as far as the sieve F, and this hopper-body and its chamber H are also provided with projecting brackets p p, which can be actuated by agitators I I, that are rotated by connections with the driving - shafts. 75 Within the hopper D, I prefer to place a stirring-wheel J, having projecting blades, the shaft of said stirring-wheel receiving rotary motion by a belt connection from the shaft E, said belt connection being indicated by 80 dotted lines in Fig. 1. It is quite evident that instead of the belt connections herein mentioned, and indicated in the drawings, other means for imparting rotary motion to the wheels and agitators and shafts may be 85 substituted without departing from the spirit of my invention.

Below the sieve F and below the upper layer of the endless apron f are stationary 90 hopper-like vessels L and M, which are intended to conduct any powder that does not reach the substances to be covered to a receptacle placed beneath the apron.

This being, in general, the construction of my machine, its operation is as follows: The 95 powder-enamel or other powder to be spread upon the plates or articles carried by the apron f is first placed into the hopper D. The iron plates or articles to be powdered are then deposited upon the apron f. The machine being then set in operation, by revolving the main driving-shaft N the apron f is

moved in the direction of the arrow shown in Fig. 1, carrying the metal plates or things to be powdered along in the same direction underneath the sieve F. By means of the screw or 5 screws l the flaps k are then spread to the desired extent, so that the powder from within the hopper D is discharged into the sieve F, through the meshes of which it is forced by the rotating brushes n, so that it will be deposited in substantially even layers upon the plates or articles carried by the apron. Any coarse admixtures of the powder that are 10 unable to pass through the meshes of the sieve may at proper intervals be removed from the 15 sieve through an opening r in the side wall thereof, which opening during the operation is closed by a suitable door or slide. During the action of the machine the sieve is shaken by the agitator, and also the hopper, to insure 20 the proper discharge of the powder therefrom, and to also impart to the brushes at varying places a firmer grip upon the walls of the sieve. Any powder which is not deposited upon the plates or articles carried by 25 the apron f will pass through the stationary guide-hoppers L M into a receptacle placed beneath them or into a heap on the floor. Suitable means for promptly stopping the machine may be devised, also for quickly setting it in motion.

What I claim is—

1. In a machine for powdering plates, fabrics, and the like, the combination of an up-

per hopper D, and means, substantially as described, for agitating the same, with the 35 receiving-sieve F, and means, substantially as described, for agitating the same, brushes n, within said sieve, and means, substantially as described, for revolving said brushes, and with a lower endless apron f beneath said 40 sieve and adapted to receive powder directly from said sieve, and means, substantially as described, for moving said apron, all arranged for operation substantially as herein shown and described.

2. The combination of the hopper D and its adjustable flaps K K, with the sieve F, brushes n, mechanism, substantially as described, for revolving said brushes, and mechanism, substantially as described, for agitating said sieve F, and with the endless apron f, all arranged for operation substantially as herein shown and described.

3. The hopper D, and means, substantially as described, for agitating it laterally, combined with the adjustable flaps K at its outlet, and means, substantially as described, for supporting said flaps in stationary support and for setting the flaps at varying distances apart, substantially as herein shown 55 and described.

HUBERT CLAUS.
